I claim the ornamental design for a slatwall frame, as shown and described.

DESCRIPTION

FIG. 1 is a top, front, left side, perspective view of a slatwall frame with bottom rail, top rail, and side rails.

FIG. 2 is a right side elevation view of the slatwall frame, bottom rail, top rail, and side rails of 1, the left side being a mirror image of the slatwall frame of FIG. 2.

FIG. 3 is a front elevation view of the slatwall frame, bottom rail, top rail, and side rails of FIG. 1.

FIG. 4 is a rear elevation view of the slatwall frame, bottom rail, top rail, and side rails of FIG. 1.

FIG. 5 is a top plan view of the slatwall frame, bottom rail, top rail, and side rails of FIG. 1, the bottom plan view being a mirror image of the slatwall frame of FIG. 5.

FIG. 6 is a cross section detail view of the top rail of FIG. 1 taken along line 6-6 of FIG. 1, shown at an enlarged scale.

FIG. 7 is a cross section detail view of the bottom rail of FIG. 1 taken along line 7-7 of FIG. 1, shown at an enlarged scale; and,

FIG. 8 is a cross section detail view of one of the side rails of FIG. 1 taken along line 8-8 of FIG. 1, shown at an enlarged scale.

The dominant features of my design reside in a top rail, a bottom rail, and side rails to be used in combination with a slatwall frame.
